UNITED STATES PATENT OFFICE.

EVA CAPLAN, OF PHILADELPHIA, PENNSYLVANIA.

LADY'S CAP.

Application filed March 5, 1929. Serial No. 344,324.

My invention relates to new and useful improvements in a lady's cap and has for one of its objects to provide an exceedingly simple and effective construction for use as 5 a boudoir or dusting cap, which when in use, will protect the wearer's head and particularly the hair, from dust as well as keeping the hair in order.

Another object of the invention is to produce a cap of this character from a single 10 piece of material which is foldable in a unique manner and which when unfolded will lie flat, or substantially so, for laundering purposes.

15 A further object of the invention is to provide a parabola shaped sheet or body, the corners of which are foldable upon an intermediate part to produce a cap, with the portions between said ends and the points 20 of fastening tucked or folded in, so that a complete enclosure is provided for protection against dust and the like.

With these ends in view, this invention 25 consists in the details of construction and combination of elements hereinafter set forth and then specifically designated by the claims.

In order that those skilled in the art to 30 which this invention appertains may understand how to use and make the same, I will describe its construction in detail, referring by numerals to the accompanying drawings forming a part of this application, in which:—

35 Fig. 1, is a perspective view of a lady's cap constructed in accordance with my invention looking at the inside, showing the folded-in portions unattached and a part of the cap broken away in the region of the 40 back to show the location of the elastic band.

Fig. 2, is a perspective view of the cap shown upon a person's head.

Fig. 3, is a view similar to Fig. 1 of a slight modification.

45 Fig. 4, is an inside face or plan view of the sheet of material or body from which the cap is formed.

In carrying out my invention, particular 50 reference will be first made to Figs. 1, 2 and 4 wherein 5 represents the body of the cap or a sheet of material fashioned into a parabola shape providing a substantially straight front edge 6, and arcuate or convex side edges 7 and 8 meeting at the back or rear 55 end of the longitudinal center of the body.

At the corners of the body are formed

button holes 9 and 10 for coaction with buttons 11 and 12 respectively located on the outside surface of the body along the arcuate edges adjacent the rear or back portion 60 thereof. Other fastening means may be used in lieu of the buttons and button holes.

Between each button hole and its respective button and preferably closer to the button hole than the button is a fastening device 65 13 on the inside face of the body and said fastening device is preferably a member of a snap fastener adapted for engagement with a complementary fastening member 14 along the front straight edge of the body 70 and substantially the same distance from a corner as the member 13 is from the same corner.

Where the material from which the cap is to be formed is of very thin fabric, a binding 75 15 may be used. The cap may be ornamented by suitable devices, such as a ruffle 16.

Preferably the rear portion of the body has an elastic band 17 inserted between two points 80 at opposite sides forward of the fastening devices or buttons 11 and 12 in order that the rear part of the cap may be stretched so as to fit different sized heads and the ends of the band being fixed forward of the buttons 11 and 12 any pull on the folded-in portions will 85 not separate the fastenings 13 and 14, and if said elastic band is left in the cap during laundering thereof, the body will lie flat except where the elastic band has the rear portion puckered, but if said elastic band is removed, then the body will lie absolutely flat 90 as shown in Fig. 4 and may be readily ironed.

To form the body into a cap as shown in Figs. 1 and 2, the corners are folded back until the button holes 9 and 10 can be placed 95 over the buttons 11 and 12 respectively, thus producing a double ply folded-in portion 18 of substantially triangular shape as shown in Fig. 1 and if said folded-in portions are provided with the fastening devices 13, they 100 may be caused to engage the complementary fastening devices 14 in order to hold said folded-in portions snugly against the end portions of the front edge and the excess length of the material between a button, as the button 12 and the fastening device 13 will be taken up by that part of the elastic band between said button 12 and its point of attachment to the cap body.

In use, the forward edge of the body will 110 lie across the forehead of the wearer while that part of the body carrying the elastic

band will lie around the rear of the head and the three plies of material forming each folded-in portion will be pressed together so as to securely close the space between the corners of the front part of the body and the sides thereof when the former are folded over on the latter, thereby preventing entrance of dust or the like to the interior of the cap while in use.

10 That portion of the elastic band between the buttons 11 and 12 will pucker the rear part of the cap but allows the same to be straightened out to the extent of the material of the body between said buttons so that the 15 cap will be automatically adjusted to different sizes.

It will be readily understood that if desired, the elastic band can be eliminated but the cap will then be of a certain different size.

20 Where the elastic band is not used, the two button holes 9 and 10 at the corners of the body may be caused to engage a single button 19 as shown in Fig. 3 in which instance the button 19 is located at the rear of the body 25 on the median line thereof or at the point where the two arcuate side edges met.

Exactly the same principle is embodied in this form of the invention and the two folded-in portions 20 are provided which are slightly 30 larger than the folded-in portions 18 but still are of triangular outline. In order to illustrate the several arrangements which can be employed, I have not shown fastening devices, such as 13 and 14 in Fig. 3, but it will 35 be obvious from the description above that such fastening devices can be applied to the form shown in Fig. 3 without the necessity of further illustration.

In this form of the device, the forward 40 straight edge of the body is given a predetermined length, thus determining the size of the cap which will be formed by the folding of the body.

A distinct feature of my invention is that 45 the cap does not have to be formed prior to placing the same upon the head as it can be thrown back upon the head similar to a bandana or shawl and the corners then folded over on the back of the body and buttoned 50 in place. By reversing the above actions, the cap can be removed. The advantage of placing the cap upon or removing the same from the head of the wearer is that the hair will not be disarranged.

55 It might be well to state at this time that the particular feature of my invention which is to be noted is that in folding the corners of the body over on the side edges or rear portion of the body, two folded-in sections are 60 produced which positively close any opening which might otherwise exist between the folded over portions so as to prevent the

entrance of dust or similar material to the interior of the cap while in use.

Of course I do not wish to be limited to 65 the exact details of construction as herein shown, as these may be varied within the limits of the appended claims without departing from the spirit of my invention.

Having thus fully described my invention, 70 what I claim as new and useful is:—

1. A cap formed from a substantially parabola shaped body, having means at the corners and side edges for connecting said corners to said side edges with the intermediate portions folded in, and an elastic band 75 at the edge to contract the arcuate edge of said body thereby producing a fullness in the back part of the cap crown.

2. The structure set forth in claim 1 in 80 combination with separable fastening means carried by the front edge of the body and the intermediate portions which are folded in to provide for attaching said folded-in portions to the front edge of the body.

85 3. A cap formed from a sheet of fabric to produce a body having a front straight edge and front side corners, the corners of said body being folded over the side edges thereof and connected thereto by separable fastening means at the corners and points intermediate the ends of the side edges in separated relation to each other, the intermediate portions of said folded-over parts being folded in, separable fastening means to attach said folded-in portions to the front edge 90 of the body and an elastic band in the edge of the body between points forward of the fastening means on the side edges of said body for the purpose stated.

95 4. A cap formed from a substantially parabola shaped sheet of material providing a front edge and arcuate convex side edges meeting at the rear on the median line of the body, an elastic band in the rear portions 100 of the side edges with the ends fixed to the body for gathering the material of the body between said ends, fastening means at the corners for separable engagement with fastening means along the side edges on the outer surface of the body and rearward of the attached ends of the elastic band when said corners are folded over the outside of the side edges of said body and the intermediate portions of said folded over parts projecting 110 inside of said folded over parts.

115 5. The structure set forth in claim 4 in combination with means for fastening the folded-in portions to the front edge of the cap body.

120 In testimony whereof, I have hereunto affixed my signature.

EVA CAPLAN.
